UNITED STATES PATENT OFFICE.

CHARLES LEO FITZ, OF FOND DU LAC, WISCONSIN, ASSIGNOR TO DROP HEAD PROJECTOR COMPANY, OF FOND DU LAC, WISCONSIN, A CORPORATION OF WISCONSIN.

DESIGN FOR A CASING FOR A PORTABLE MOTION-PICTURE MACHINE.

Application filed November 3, 1922. Serial No. 4,215. Term of patent 14 years.

To all whom it may concern:

Be it known that I, CHARLES L. FITZ, a citizen of the United States of America, resident of and residing at Fond du Lac, in the county of Fond du Lac and State of Wisconsin, have invented a new, original, and ornamental Design for a Casing for a Portable Motion-Picture Machine, of which the following is a specification, reference be-

ing had to the accompanying drawing, forming a part hereof, and which represents a perspective view of my new design for a casing for a portable motion-picture machine.

I claim:

The ornamental design for a casing for a portable motion picture machine, as shown.

CHARLES LEO FITZ.
